T. P. ANTHONY.
MOLD DRYING PROCESS.
APPLICATION FILED NOV. 2, 1918.

1,325,972.

Patented Dec. 23, 1919.

UNITED STATES PATENT OFFICE.

THOMAS P. ANTHONY, OF EDGEWATER PARK, NEW JERSEY. ASSIGNOR TO UNITED STATES CAST IRON PIPE & FOUNDRY COMPANY, OF BURLINGTON, NEW JERSEY, A CORPORATION OF NEW JERSEY.

MOLD-DRYING PROCESS.

1,325,972.

Specification of Letters Patent. Patented Dec. 23, 1919.

Application filed November 2, 1918. Serial No. 260,897.

To all whom it may concern:

Be it known that I, THOMAS P. ANTHONY, a citizen of the United States of America, and resident of Edgewater Park, in the 5 county of Burlington and State of New Jersey, have invented a certain new and useful Improvement in Mold-Drying Processes, of which the following is a true and exact description, reference being had to the accompanying drawings, which form a part 10 thereof.

My invention relates to the drying of pipe molds, and has for its object to provide a rapid and efficient method of drying the 15 pipe molds, which is especially well adapted for drying the molds in approximately the position they are to occupy during the casting operation.

Essentially my invention consists in placing 20 the mold flask, with its lining of undried mold, in a vertical position, closing the top of the mold and introducing burning gases into the bottom of the mold at some distance from its sides, causing the burning gases to pass upward through the central portion of 25 the mold to its top, then downward along the sides of the mold to its bottom where ample space is left for its lateral escape.

By preference, the mold flask is arranged 30 with its bell end downward and above and at some distance from, but concentric with, the mold members which coact with the bell in the assembled mold, so that the hot gases will escape from the mold flask between 35 its bell end and the said coacting mold members, with the result that all the parts of the mold are simultaneously dried.

Reference being now had to the drawings, 40 which illustrate my invention, and certain convenient mechanical appliances for its practice, and in which—

Figure 1 is a vertical sectional elevation 45 showing the mold flask and coacting mold members together with the supporting mechanism and the appliances for introducing air and gas.

Fig. 2 is a similar section to Fig. 1, showing 50 the mold members assembled, the core in place, the casting completed, and the appliances in the position they occupy during the casting operation, and

Fig. 3 is a plan view of the base of the structure shown in Figs. 1 and 2.

A indicates the mold flask having a bell

mouth, as indicated at A'. B is the mold 55 supported in the flask and having its bell mouth B'. C is the bottom plate of the mold having, as shown, a seat C' for the annular socket iron and a recess C² to contain molding sand as indicated at D. E is 60 the annular socket iron, the outer face of which supports the molding sand F, which coacts with the bell end B' of the sand lining B to make up the mold for the bell. G represents one of several separating blocks, 65 which, during the drying of the mold, rest upon the bottom plate C and support the mold flask at some distance above it. By preference I form these blocks with perforations as indicated at G', so that gases 70 can pass freely through them as well as between them. H H represent what may be called the legs of the stool or base. By preference I use four or six symmetrically disposed and continued upward in the form 75 of supporting ribs H', preferably formed with a series of concentric annular notches, as indicated at h', to fit different sizes of bottom plates C. The ribs H' and legs H are connected together by web plates H², 80 which slope gradually outward and upon which a layer of sand, held in place by projections indicated at I, is advantageously placed as shown in Fig. 1, as a protection 85 against runouts. H³ is an annular chamber supported, as shown, by the ribs H' and fed with gas through a passage H² and gas pipe J. H⁵ indicates an annularly arranged system of gas burners extending upward from the chamber H³. K indicates the support 90 for an annular deflector indicated at K'. The support is preferably cylindrical in form and made so as to fit against a cylindrical inner face at the end of the chamber H³. It is provided, as shown, with depending legs K², which, during the drying operation rest upon blocks L, as shown in Fig. 1, said blocks being removed and the cylinder and supported deflector brought to the position shown in Fig. 2 during the casting 95 operation. M is a cover plate which closes the upper end of the mold during the drying operation. N, Fig. 2, represents the core bar having trunnions as indicated at N' and N².

For the drying operation the parts are assembled as shown in Fig. 1. Gas is fed to the annular system of burners and directed

upward against the baffle K', which forces it to move outward into the entering air current which passes freely through the space between the bottom plate C and the web H². The ignited air and gas pass upward through the central portion of the mold, as indicated at O, turning outward at the top of the mold against the cover plate M, as indicated at O', and then pass downward as indicated at O² in contact with the molding sand to be dried, finally passing between the bell mouth B' and the mold members F and D and outward between and through the spacing blocks G.

15 I have found that a good and efficient circulation of the burning gases is effected in this way, and that both the radiant and sensible heat of the gases is effectually used for the drying of the molds.

20 In Fig. 2 I have found the parts in the position they occupy during the casting operation, and it will be observed that the only changes in position of the parts involved is the removal of the spacing blocks G, permitting the flask to rest upon the bottom plate C, and the removal of the supporting blocks L, which permits the cylinder K and deflector K' to assume the position as shown. This will indicate an advantageous feature 25 incident to the practice of my new method of drying molds in that it enables them to be dried approximately in the positions which they occupy during the casting operation.

30 35 Having now described my invention, what I claim as new and desire to secure by Letters Patent, is:

1. The method of drying long open ended pipe molds consisting in placing the mold in

a vertical position, covering the top of the 40 mold to prevent escape of gases therethrough, introducing burning gases at the bottom of the mold at some distance from the sides thereof and providing an outlet 45 passage for the gases in free communication with the outer periphery of the lower end of the mold, whereby said burning gases are caused to pass upward through the central part to the top of the mold and downward along the sides of the mold to escape at the 50 bottom thereof.

2. The method of drying long open ended pipe molds consisting in supporting the mold in a vertical position with its lower end in free lateral communication with the 55 atmosphere, covering the top of the mold to prevent escape of gases therethrough, introducing burning gases at the bottom of the mold at some distance from the sides thereof whereby said burning gases are 60 caused to pass upward through the central part to the top of the mold and downward along the sides of the mold to escape laterally at the bottom thereof.

3. The method of drying pipe molds, 65 which consists in supporting the mold flask vertically above and with its bell end at some distance from and concentric with the mold members which coact with said bell end in the assembled mold, covering the top 70 of the mold, introducing burning gases at the bottom of the mold flask and at a distance from its inner sides, whereby said burning gases are caused to pass upward to the top of the mold, downward along its 75 inner sides, and out between the bell end of the flask and the said other mold members.

THOMAS P. ANTHONY.
